UNITED STATES PATENT OFFICE

WALTER S. ADAMS AND ELMER LATSHAW, OF PHILADELPHIA, PENNSYLVANIA, AS
SIGNORS TO THE J. G. BRILL COMPANY, OF PHILADELPHIA, PENNSYLVANIA, A
CORPORATION OF PENNSYLVANIA

VESTIBULE MOUNTING FOR HIGH-SPEED ARTICULATED CARS

Application filed August 28, 1929. Serial No. 389,004.

This invention relates to vestibule mountings for articulated cars and more particularly to that type of vestibule mounting wherein the vestibule is supported entirely 5 from the truck which forms a common mounting for adjacent ends of car bodies.

An important object of the invention is to provide a construction which will at once support the vestibule independently of the car 10 bodies, maintain the balance of the vestibule and resist displacement thereof at all times and which will insure coordination of the movements of the vestibule and the truck so that the vestibule will remain in the proper 15 position with relation to the cars.

A still further object of the invention is the provision of a structure of this character permitting the vestibule to be bolted to the truck and providing a construction wherein the 20 weather stripping associated with the vestibule may be carried entirely by the vestibule and simply guided from the car.

A still further object of the invention is the production of a structure of this character 25 which may be relatively cheaply produced and in which the installation and removal of the vestibule are facilitated.

These and other objects we attain by the construction shown in the accompanying 30 drawings wherein, for the purpose of illustration, we have shown a preferred embodiment of our invention and wherein:

Fig. 1 is a plan view of a vestibule mounting for articulated cars constructed in accordance with our invention;

Fig. 2 is a vertical sectional view on line 2-2 of Fig. 1; and

Fig. 3 is a semi-diagrammatic view showing the vestibule structure in position between connected cars.

Referring now more particularly to the drawings, the numeral 10 generally designates a truck bolster supporting the adjacent ends of cars 11 and providing a pivotal 45 mounting therefor. In the present illustration the supporting construction employed is substantially identical with that illustrated in the application of Walter S. Adams for patent on pivot for articulated cars filed August 19, 1928, Serial No. 298,527, now Patent No.

1,732,998, granted October 22, 1929, each car 11 being equipped with a socket-engaging element 12 extending into a socket 13 formed in a block 14 mounted upon a plate 15 having an annular retaining flange 16. The sole difference between the structure of plate 15, as 55 illustrated in the application above identified and the present structure lies in the fact that this plate is formed at its center with an up-standing hub-forming flange 17. The hub-forming flange 17 and peripheral or retaining flange 16 combine to produce an annular channel within which the blocks 14 are rotatable so that the effective pivotal connection 60 of the car lies at the center of the plate 15. 65

This hub together with a truck bolster are provided with aligned bores permitting loose passage of a king bolt 18. The vestibule 19 embodies a central casting 20 having a squared polygonal socket 21 to receive and fit the head of king bolt 18. Between the bottom of this casting and the upper end of hub flange 17 a spring 22 surrounds the king bolt, 70 said spring being compressed in installation to a load in excess of the vestibule weight and possible passenger loads imposed thereon. The lower end of the bolt is keyed as at 23 against rotation with relation to the truck bolster so that the bolt 18 will turn with the truck and through its head and plate 20 will 75 turn the vestibule therewith. The loose mounting of the bolt in its bore with the truck and hub flange 17 will permit necessary oscillation of the vestibule about the pivot formed by key 23 to accommodate normal 80 relative movements of the cars 11 and spring 22 will act to return the vestibule to its normal position when displaced and to retain it 85 at all times in such normal position.

By mounting the vestibule in this manner, 90 space is provided beneath the vestibule for the convenient mounting of springs 24 which engage the lower ends of weather stripping 25 to maintain this weather stripping against the vestibule frame. By employing a similar 95 mounting at the top of the car the use of compression springs with the strip guides 26 of the car body where they are relatively inaccessible is eliminated, a longer spring can be employed so that more efficient operation 100

of the weather stripping may be had and the installation of the stripping is greatly facilitated. Springs 24 may conveniently have their inner ends secured to casting 20 as at 27.

It will be obvious that a structure of this character may be conveniently and cheaply manufactured and at the same time affords all the advantages afforded by the ordinary vestibule mounting. It will also be obvious that this structure is capable of a considerable range and change of modification without departing from the spirit of my invention, we accordingly do not limit ourselves to the specific mounting herein illustrated except as hereinafter claimed.

15 We claim:

1. In combination with a single truck adapted to receive and support the adjacent ends of cars, a drum vestibule for the cars arranged above the truck and a single spring centrally engaging the truck and axially engaging the drum constituting the sole means supporting the drum from the truck.

2. In combination with a single truck adapted to receive and support the adjacent ends of cars, a drum vestibule for the cars arranged above the truck and a single spring centrally engaging the truck and axially engaging the drum constituting the sole means supporting the drum from the truck, the drum having a centrally disposed casting apertured for the passage of a king bolt and a king bolt extending through the casting and engaging the truck for limiting separation of the truck and drum.

3. In combination with a single truck adapted to receive and support the adjacent ends of cars, a drum vestibule for the cars arranged above the truck and a single spring centrally engaging the truck and axially engaging the drum constituting the sole means supporting the drum from the truck, the drum having a centrally disposed casting apertured for the passage of a king bolt and a king bolt extending through the casting and engaging the truck for limiting separation of the truck and drum, said bolt being held against rotation with relation to each of the drum and truck.

4. In combination with adjacent ends of cars, a truck, a drum vestibule for connecting the ends of the cars and concentric bearing supports for the car ends and the drum, the support of the drum constantly urging said drum to a vertical position while permitting yielding thereof.

5. In combination with adjacent ends of cars, a truck, a drum vestibule for connecting the ends of the cars, concentric bearing supports for the car ends and the drum, the support of the drum constantly urging said drum to a vertical position while permitting yielding thereof, and a single means limiting separation of the truck and vestibule and holding the same against relative rotation.

6. In combination with adjacent ends of cars, a truck, a drum vestibule for connecting the ends of the cars, concentric bearing supports for the car ends and the drum, the support of the drum constantly urging said drum to a vertical position while permitting yielding thereof, and a bolt extending through the support and having non-rotative engagement with the drum and truck.

7. In combination with adjacent ends of cars, a truck, a drum vestibule for connecting the ends of the cars and concentric bearing supports for the car ends and the drum, the support of the drum constantly urging said drum to a vertical position while permitting yielding thereof, said support engaging the drum axially thereof.

8. In combination with adjacent ends of cars, a truck, a drum vestibule for connecting the ends of the cars, concentric bearing supports for the car ends and the drum, the support of the drum constantly urging said drum to a vertical position while permitting yielding thereof, said support engaging the drum axially thereof, and a single means limiting separation of the truck and vestibule and holding the same against relative rotation.

9. In combination with adjacent ends of cars, a truck, a drum vestibule for connecting the ends of the cars, concentric bearing supports for the car ends and the drum, the support of the drum constantly urging said drum to a vertical position while permitting yielding thereof, said support engaging the drum axially thereof, and a bolt extending through the support and having non-rotative engagement with the drum and truck.

10. In combination with a single truck adapted to receive and support the adjacent ends of cars, a drum vestibule for the cars arranged above the truck, a single spring centrally engaging the truck and axially engaging the drum constituting the sole means supporting the drum from the truck, and a bolt extending through the spring and having non-rotative engagement with the drum and truck.

11. In combination with a single truck adapted to receive and support the adjacent ends of cars, a drum vestibule for the cars arranged above the truck, a single spring centrally engaging the truck and axially engaging the drum constituting the sole means supporting the drum from the truck, and a single means limiting separation of the truck and vestibule and holding same against relative rotation.

12. In combination with a single truck, a bearing element supported thereby having a central aperture and a surrounding concentric bearing groove, bearing elements oscillatable in said grooves and adapted to receive and support the adjacent ends of cars, a drum vestibule for the cars arranged above the

truck, a spring extending between the bearing element and the drum and engaging the drum and bearing element axially thereof, said spring constituting the sole supporting means for the drum.

13. In combination with a single truck, a bearing element supported thereby having a central aperture and a surrounding concentric bearing groove, bearing elements oscillatable in said grooves and adapted to receive and support the adjacent ends of cars, a drum vestibule for the cars arranged above the truck, a spring extending between the bearing element and the drum and engaging the drum and bearing element axially thereof, said spring constituting the sole supporting means for the drum, and a bolt extending through the central aperture of the bearing element and engaging the truck to limit separation of the bearing element and truck, said bolt permitting limited oscillation of the drum.

14. In combination with a single truck, a bearing element supported thereby having a central aperture and a surrounding concentric bearing groove, bearing elements oscillatable in said grooves and adapted to receive and support the adjacent ends of cars, a drum vestibule for the cars arranged above the truck, a spring extending between the bearing element and the drum and engaging the drum and bearing element axially thereof, said spring constituting the sole supporting means for the drum, and a bolt extending through the central aperture of the bearing element and engaging the truck to limit separation of the bearing element and truck, said bolt permitting limited oscillation of the drum, said bolt having nonrotative engagement with the truck and drum.

15. In combination with the adjacent ends of cars supported by a common truck, a vestibule overlapping the ends of the cars, a single spring supporting the vestibule from the truck at the center thereof and means connecting the truck and vestibule preventing separation thereof.

16. In combination with the adjacent ends of cars supported by a common truck, a single spring extending upwardly from the truck between the car ends, a vestibule supported therefrom and means connecting the truck and vestibule for limiting separation of the vestibule from the truck.

17. In combination with the adjacent ends of cars supported by a common truck, a single spring extending upwardly from the truck between the car ends, a vestibule supported therefrom and means connecting the truck and vestibule for limiting separation of the vestibule from the truck, said means permitting a limited oscillation of the vestibule with relation to the truck.

18. In combination with adjacent ends of cars supported by a common truck, a bolt

loosely directed through the truck and held against rotation with relation thereto, the vestibule having at its center a casting in which the head of the bolt is engaged and a spring surrounding the bolt between the truck and said casting and constituting the sole support for said vestibule.

19. In combination with adjacent ends of cars supported by a common truck, a bolt loosely directed through the truck and held against rotation with relation thereto, the vestibule having at its center a casting in which the head of the bolt is engaged and a spring surrounding the bolt between the truck and said casting and constituting the sole support for said vestibule, said bolt being held against rotation with relation to the vestibule and truck.
